US0D1042113S

(12) **United States Design Patent** (10) **Patent No.:** **US D1,042,113 S**
(45) **Date of Patent:** **** Sep. 17, 2024**

(54) **REINFORCING CARTON**

- (71) Applicant: **Graphic Packaging International, LLC**, Atlanta, GA (US)
- (72) Inventors: **Raymond S. Kastanek**, Mead, CO (US); **Kelly R. Fitzwater**, Lakewood, CO (US)
- (73) Assignee: **Graphic Packaging International, LLC**, Atlanta, GA (US)
- (**) Term: **15 Years**
- (21) Appl. No.: **29/737,403**
- (22) Filed: **Jun. 9, 2020**

Related U.S. Application Data

- (63) Continuation of application No. 16/751,761, filed on Jan. 24, 2020, now Pat. No. 11,198,534.

(57) **CLAIM**

The ornamental design for a reinforcing carton, as shown and described.

DESCRIPTION

FIG. 1 is a perspective view of a reinforcing carton showing my new design.

FIG. 2 is a front elevation view of the reinforcing carton of FIG. 1; the rear elevation view is identical.

FIG. 3 is a left elevation view of the reinforcing carton of FIG. 1; the right elevation view is identical.

FIG. 4 is a top plan view of the reinforcing carton of FIG.

1.

FIG. 5 is a bottom plan view of the reinforcing carton of FIG. 1.

FIG. 6 is a plan view of the reinforcing carton of FIG. 1 in a flattened configuration; and,

FIG. 7 is a plan view of the reinforcing carton of FIG. 1 shown in an unfolded configuration.

1 Claim, 7 Drawing Sheets
